UNITED STATES PATENT OFFICE.

MARIUS LATOUR, OF PARIS, FRANCE

DEVICE FOR HIGH-FREQUENCY SIGNALING.

Application filed July 17, 1920. Serial No. 397,140.

(GRANTED UNDER THE PROVISIONS OF THE ACT OF MARCH 3, 1921, 41 STAT. L., 1313.)

To all whom it may concern:

Be it known that I, MARIUS LATOUR, citizen of the Republic of France, residing at 79 Boulevard Haussmann, Paris, in the Republic of France, have invented certain new and useful Devices for High-Frequency Signaling, of which the following is a specification.

The following foreign applications have been filed—France, dated October 26, 1916, Patent #503,076; Germany, dated July 9, 1920; England, dated July 10, 1920, Patent #148,955; Belgium, Patent #288,301, dated June 29, 1920; Denmark, dated June 21, 1920; Holland, dated September 7, 1920; Italy, dated July 8, 1920; Poland, dated August 7, 1920, and Sweden, dated June 28, 1920.

My invention relates to high frequency telephone systems with particular reference to such systems in which a high frequency alternator is used as a source the current of which is controlled in accordance with the vibrations of the human voice.

The principle of my invention is to act on the excitation of the alternator by means of rectified high frequency current. This high frequency current, before it has been rectified, is more suitable to be acted upon by any voice actuated device than direct current would be. It is then rectified in order to be easily passed through the exciting winding whose impedance to high frequency current may be high.

My invention is, for the purpose of clearness, set down in the appended drawing, where:

Figure 1 is a view showing more or less diagrammatically one embodiment of the invention.

Fig. 2 is a modification in which means are provided to amplify the exciting current.

Fig. 3 is a further embodiment of the invention.

In the two figures of the drawings, in which the same letters are employed to designate the same parts, 1, 2, are the terminals used for the purpose of connection with the exciting current source (not shown); 3, 5, are two induction coils, 4, 6, are two condensers, 7 is a transformer, 8 is the exciting winding of the high frequency alternator,

9 is the rectifier, 10 is a microphone transformer, 11 is a voice actuated device. 55

In the embodiment shown on Fig. 1 the high frequency current from the source (not shown) connected to terminals 1 and 2 flows through a tuned circuit comprising condensers 4 and 6 and the iron core inductance 60 coils 3 and 5; these coils are provided with an additional winding which is part of a circuit comprising also a voice actuated device 11 and a direct current source.

The voice actuated device may, as has been 65 shown, be connected with the circuit by means of a suitable transformer.

The high frequency current is then rectified by means of a vapor rectifier 9 connected according to a known disposition with 70 the exciting winding of the high frequency alternator.

The effect of the voice currents in the additional winding of coils 3 and 5 is, as well known, to modify the tuning of the high frequency circuit and consequently to vary the impedance of the high frequency circuit connected across terminals 1 and 2. The result will then be that the telephone current will indirectly cause the exciting current of the 75 alternator to vary.

Coils 3 and 5 may be combined with the transformer by giving the winding of the latter a corresponding number of turns and by suitably devising the magnetic core. The 80 microphone may be protected against exaggerated high frequency currents, by provision of a choke coil or, still better, of a stopper circuit tuned to the frequency of the 85 high frequency current.

It is to be said that the current, once rectified, may be passed again around the magnetic core of the coils 3 and 5. The latter disposition is shown in Fig. 2. In this way, 90 the effect obtained is to a large extent amplified. If this phenomenon be exaggerated, it must be noted that a self exciting system is obtained, which is adapted to generate sustained oscillations.

The high frequency current brought to the terminals 1 and 2 may be that generated by the high frequency alternator itself. In this case, a self-exciting system is obtained, the stability of which may be exactly regulated by suitably modifying the return coupling 100 action of the rectified current on the current

in coils 3 and 5. The two windings on each of these coils may be combined into one.

In the case of the embodiment shown in Fig. 1, in order that current may be generated into the antenna only during actual speech in the microphone and may fall to a negligible quantity during the silent intervals, there will be provided a permanent inverse excitation of the alternator, adapted to 10 balance the residual excitation caused by the current rectified during the silent intervals. This balancing excitation may be applied, either to winding 8, or to an additional winding.

15 The inverse permanent energization is shown in Fig. 3 by means of a circuit 20 comprising a direct current source and a winding controlling the energization of the alternator in a manner to annul the effect 20 produced by the rectified current which traverses the winding 8 when the telephone transmitter 11 is not actuated by speech.

In order not to render the device too complicated, the same result could be obtained 25 by feeding the exciting winding through a transformer, instead of inserting it directly in circuit 8, 9. This transformer would be analogous to a microphone transformer.

30 A direct electromotive force working in series with the high frequency electromotive force may be provided, in order to balance the polarizing electromotive force of the rectifier.

35 When receiving signals modulated by means of such a device, it will be advantageous to superimpose on the received current a locally generated current of the same frequency and of a higher intensity. The

resulting intensity thus obtained will then oscillate between two values, the difference 40 between which will be superior to the intensity of the received current, both currents at times helping each other and at other times opposing each other. In fact, the intensity of signals would thus be increased 45 in such a manner as to allow reception with receiving stations, by which the current of the transmitter alone could not be detected, on account of its being too feeble.

Having thus described my invention, what 50 I claim as new and desire to secure by Letters Patent is:

1. In the art of signaling by means of a high frequency alternator and the like, a method consisting in modulating the mean 55 amplitude of a high frequency alternating current, in rectifying the thus modulated high frequency current and in feeding the exciting circuit of the alternator with the thus modulated and rectified high frequency 60 current.

2. A high frequency signaling system comprising, in combination, a high frequency alternator, a rectifier connected with the exciting winding of said high frequency 65 alternator, a transformer the secondary winding of which is connected with said rectifier and exciting winding and the primary winding of which is part of an oscillating circuit comprising iron core inductances, the 70 said iron core inductances being provided with additional windings connected with a voice actuated device.

In testimony whereof I affix my signature.

MARIUS LATOUR.
